UNITED STATES PATENT OFFICE.

JOHN J. COONEY, OF NEW YORK, N. Y., ASSIGNOR TO SAFETY WINDOW COMPANY, OF NEW YORK, N. Y., A CORPORATION OF NEW YORK.

WINDOW.

1,124,298.

Specification of Letters Patent.

Patented Jan. 12, 1915.

Application filed December 26, 1913. Serial No. 808,743.

To all whom it may concern:

Be it known that I, JOHN J. COONEY, a citizen of the United States, residing at New York, in the county of New York and State of New York, have invented certain new and useful Improvements in Windows, of which the following is a full, clear, and exact description, such as will enable others skilled in the art to which it appertains to make and use the same.

This invention relates to windows, doors, etc., and with respect to its more specific features, to devices of the character referred to which are adapted not only to slide relatively to the opening they are designed to protect, but also to have movement in a direction away from the plane of the window-opening or door-opening, thereby involving features similar to those of a casement.

One of the objects of the invention is the provision of a simple arrangement whereby a sliding door or window may not only have its normal sliding movements in a plane generally parallel to the plane of the opening, but also movement at an angle to said plane.

Another object of the invention is the provision of a practical device of the character referred to and involving hinge elements through the instrumentality of which the door or window may be moved at an angle to the plane of the opening, the hinge elements being so constructed as to be readily thrown out of normal operative position when not in use and into operative position when it is intended to use the same.

A still further object of the invention is the provision of a simple and practical hinge element which may be readily applied to devices of the character referred to in present use and which will present a slightly appearance and may be concealed when not in use.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of this invention, and wherein similar

reference characters refer to similar parts throughout the several views,—Figure 1 illustrates the invention as applied to a window, the view being from the interior of a room; Fig. 2 is a section of Fig. 1; Fig. 3 is a perspective view showing the hinge members in extended position ready for use; Fig. 4 is a section of a portion of Fig. 1, showing a set of hinge members in engagement with each other, and the sash in open position; Fig. 5 is a section on line α — α of Fig. 4; and Fig. 6 is a detail view.

Inasmuch as the invention is well exemplified when embodied in a window, the disclosure hereof will be made in connection with such an embodiment, it being understood that the invention is equally applicable to other similar devices.

Referring now more specifically to the drawings, there are shown window elements, viz., a window-frame and sashes therefor, the numeral 1 representing a window-frame, 2 the upper sash and 3 the lower sash therefor. Said sashes are arranged to have the usual sliding movement in the window-frame in planes relatively parallel to that of the opening covered thereby. Inasmuch as the sashes 2 and 3 are, by the provisions of the present invention, designed to be movable also in planes at an angle to their normal sliding planes, and specifically to be hinged at one side so as to swing away from the plane of the window-opening and into the room or space associated therewith, it will be understood that the general construction of the window-frame is such as to permit the swinging movement referred to. As the general type of window referred to is known, it will be unnecessary to specifically describe the same, but is sufficient to refer to the patent dated November 23, 1909, No. 941,310, wherein the type of window will be found. In the present embodiment the sashes are designed to be swung on an axis at the left-hand side of the window-opening, and it will accordingly be understood that at the right-hand side the window-framing is provided with a removable section, such as 4, which is designed to swing outwardly in order that the sashes 2 and 3 may be swung outwardly on pivots or hinges at the left-hand side, as will be hereinafter described.

The sashes are provided with the usual cords and weights employed in windows of the character referred to.

to, the association of these elements with the sashes being similar to that disclosed in the patent above mentioned.

The numeral 5 indicates one member of a hinge, in this case the pintle or pivot member, and the numeral 6 indicates a member adapted to coöperate with the pintle member, the same comprising an opening 7 adapted to engage the pintle 5. Inasmuch as the hinge members are substantially the same in construction throughout, except that one is the male member and the other the female member, the description of these elements will be confined to that of the male member except as hereinafter noted. The pintle 5 forms an integral, upstanding portion of a plunger 8 mounted to reciprocate and be guided in a chamber 9. The chamber 9 is of a tubular character having preferably cylindrical inner and outer peripheral surfaces, and the peripheral surface of a portion of the plunger 8 conforms in size and shape to the inner peripheral dimensions of the chamber so as to nicely fit therein, as disclosed.

The numeral 10 represents a resilient means, as a spring, disposed within said chamber and engaging the rear portion of the plunger, a recess 11 being provided in the plunger into which said spring 10 extends. The rear end of the spring 10 abuts the end wall 12 of the chamber, and when the plunger is free to move the spring 10 will urge the same outwardly or in a direction to dispose the pintle 5 in a position wherein it will coöperate with its coöperating member 6, in which position the pintle 5 and the opening 7 will be disposed in alinement with each other, in the present instance in vertical alinement, the sashes being in their normal sliding planes.

13 represents a face plate having holes 14 for attachment to a sash or to the window-frame and provided with a non-circular guide opening 15 intersected by a slot 16, the latter being of a height sufficient to permit the pintle 5 to pass therethrough, the chamber element 9 being fixed to said plate. A reduced portion 18 of the plunger supports the pintle 5 and is of such a shape as to conform with that of the opening 15, and in this manner, in the present embodiment, the plunger 8 is prevented from rotating and thus the pintle 5 is preserved in vertical position during its movements. The plate 13 lies over the opening in the tubular chamber and serves as a fixed stop to limit the outer position of the hinge member.

The upper portion of the wall 19 of the tubular chamber 9 is recessed, as at 20, in order to provide for the reception of the pintle 5, which in the present embodiment is of such a height as to require some space at this point when in its inner position.

From the foregoing it will be perceived

that the pintle or hinge member 5 may be readily pressed by the hand toward the chamber 9, being thus displaced relative to the axis of alinement with its coöperative member, and that it will pass through the opening 16 in the plate 13, and provision is made for retaining the hinge members in the inner position just referred to, the preferred device comprising a movable abutment, stop or plate 21, preferably pivoted at 22 to the face plate 13 and disposed so that, by turning the plate 21 upon its pivot, a portion thereof may be thrown across the opening in the face plate and preferably opposite the end of the plunger portion 18, thus serving to retain the hinge member in its inner position. Preferably, also, the plate 21 is of such a character or shape as to cover and conceal the opening 15 and the slot 16. The plate 21 is relatively thin and the plunger 8 is provided with a locking element, or recess, 23, which, when the pintle 5 is in its outer position, will be disposed opposite the plate 21 and the latter may then be thrown into position to engage said recess 23 and thus prevent or restrain inner movement of the hinge member. In this manner the pintle 5 is locked in outer alining position.

It will be understood that the female member 6 of the hinge is similar in construction and operation to the male member, except that the pintle 5 is replaced by the hinge opening or bearing 7. A plate, 24 similar to 21 will, it is understood, be provided for the female hinge member and a locking notch similar to 23 may be provided therein, if desired.

In the present embodiment the window-frame is provided with four of the male hinge members, two for each sash, the members for the lower sash being applied to the inner face of the window-frame closely adjacent the lower sash and at a suitable distance apart within the vertical dimension of the lower sash. The inner bead 25 of the window-frame is similarly provided with male hinge members and preferably these are disposed at the lower portion of the window-frame so that the swinging of the upper sash may occur at a position conveniently within the reach of the person manipulating the same. Each of the window sashes is likewise provided with two female hinge members, as described, the same being disposed on the faces of the sashes and at a proper distance apart to simultaneously co-operate with the male members, respectively.

In operation, and supposing it is desired to swing the sashes outwardly from the window-opening, the plates 21, 24, are thrown up, whereupon the several hinge elements will be projected by their respective springs 10. Coöperative hinge members will then be in alinement, and upon lowering the lower sash the female members will engage the 130

- male members and, after turning out the frame portion 4, this sash may be swung at an angle to the sliding planes of the windows, under ordinary normal conditions.
- 5 The sash weight on the right-hand side will be locked against falling by the automatic catch 26 as the sash is swung outwardly from the window-frame, as provided in the patent referred to. A portion of the inner 10 bead 27 at the lower portion of the window-frame is also made bodily removable, as indicated at 28, Fig. 1, and the upper sash may be swung into the room on the hinge members provided therefor, as described,
- 15 said lower bead portion having been removed. In this manner the entire area of the window-opening may be thrown open and the air may pass freely therethrough. The sashes will have been swung inwardly 20 into the room into convenient position for repair, washing, etc. Thus, by the above-described construction, are accomplished, among others, the objects hereinbefore referred to.
- 25 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following 30 claims is intended to cover all of the generic and specific features of the invention herein described and all statements of the scope of the invention, which, as a matter of language, might be said to fall therebetween.
- 35 Having described my invention, what I claim as new and desire to secure by Letters Patent is:
- 40 1. In an apparatus of the character described, in combination, a window element 45 comprising a chamber, a face plate comprising an integral relatively fixed stop opposite said chamber and having a guide opening opposite said chamber, a rectilinearly reciprocable plunger in said chamber adapted 50 to contact said stop and having a hinge member adapted to enter said opening, a spring in said chamber adapted to urge said hinge member outwardly of said chamber
- and said plunger into contact with said stop, thereby limiting the outward movement of said hinge member, said spring being arranged to permit said hinge member to be moved to within said chamber against the resistance of said spring, and a plate pivotally connected to said window element 60 and adapted to be moved over said guide opening to conceal said opening and prevent outward movement of said hinge member when the latter is disposed in said chamber.
- 65
2. In an apparatus of the character described, in combination, a window element comprising a chamber, a face plate comprising a relatively fixed stop opposite said chamber, and having an opening opposite 70 said chamber, a rectilinearly reciprocable plunger in said chamber adapted to contact said stop and having a hinge member adapted to enter said opening, a spring in said chamber adapted to urge said member outwardly, and said plunger into contact with said stop, thereby limiting the outward movement of said member, said spring being arranged to permit said member to be moved into said chamber against the resistance of said spring, and a pivoted abutment 75 adapted to be moved into and out of position opposite said opening.
3. In an apparatus of the character described, in combination, a plate having a 80 non-circular opening, a tubular chamber secured to said plate opposite said opening and having an end wall, the peripheral wall of said chamber having a recess communicating with the opening in said plate, a 85 plunger adapted to reciprocate in said chamber and having a reduced portion provided with a pintle adapted to enter the opening in said plate, said pintle being adapted to move in line with said recess, a spring in 90 said chamber adapted to urge said plunger outwardly, and a pivoted abutment adapted to be moved into and out of position opposite said opening.
- 95
- In testimony whereof I affix my signature, 100 in the presence of two witnesses.
